CLEANING DEVICE

John W. Chamberlin and Rex Earl Bassett, Jr.,
South Bend, Ind.

Application May 19, 1939, Serial No. 274,594

11 Claims. (Cl. 15—4)

This invention relates to cleaning upholstery and other materials, especially those of a character to be cleaned most conveniently by moving a portable cleaning device over the surface of the work.

An object of the invention is to provide simple and easily manipulated means for treating with a cleaning liquid the material being operated upon, progressively, by moving a cleaning device over its surface in a manner analogous to the operation of a vacuum cleaner. To this end, from one point of view the invention may be regarded as concerned with forcing the cleaning liquid against a limited area or zone of the work, while continuously withdrawing it from an immediately adjacent area or zone, preferably by suction. Thus the cleaning liquid is continuously forced into and drawn out of the work by a cleaning device readily moved progressively across the surface of the work.

Another object of the invention is to provide a portable cleaning device in which the material to be cleaned is brushed or rubbed at the same time as it is treated with cleaning liquid. According to one important feature the brush is moved by compressed air or the like which is also used to spray the cleaning liquid onto the material.

Various features of novelty relate to the construction and arrangement of the parts of the cleaning device, and particularly in the cooperative arrangement of two adjacent nozzles (one preferably extending part or all of the way around the other) through one of which atomized cleaning liquid is forced under fluid pressure against the work, and to the other of which suction is applied to draw the liquid away from the work after its cleaning action has taken place.

Still other features relate to the arrangement of a brush in the inner nozzle and to the provision of motor means in the nozzle for rotating the brush.

The above and other objects and features of the invention will be apparent from the following description of the illustrative embodiment shown in the accompanying drawings, in which:

Figure 1 is a diagrammatic perspective view of the apparatus, the suction-producing device being shown in section;

Figure 2 is a section through the portable device which is intended to be moved by the operator over the surface of the work;

Figure 3 is a side view of another portable device; and

Figure 4 is an end view of the device of Figure 3.

In the form illustrated in Figures 1 and 2, the cleaning device includes a die-cast body 10, one end of which extends downwardly nearly at a right angle to form a handle 12, and which has a suitable lug 14 for engagement by the operator's fingers to facilitate grasping and manipulating the device.

10 A passage 16 for fluid under pressure, usually compressed air, extends through the body 10 and handle 12 to a fitting 18 adapted for connection through a conduit 20, at least part of which is flexible, to a source of pressure fluid. The source illustrated is the air tank 22 of an air compressor unit having a motor 24 driving a compressor 26 automatically controlled in the usual manner to maintain a predetermined pressure in the tank 22. The passage 16 is under the control of a spring-closed air valve 28.

20 The body 18 of the device is also formed with a right angle passage 30 for cleaning liquid. This passage extends through a boss 32 to which is attached (with a ground joint to insure that no air leakage takes place), by means such as an attaching nut 34 threaded on the end of the boss 32, at an angle approximately paralleling the handle 12, a reservoir for cleaning liquid, such as one of the carbon tetrachloride group of non-inflammable dry-cleaning liquids.

25 This reservoir includes a can-shaped body 35 adapted to be held in sealing engagement with a gasket 36 of rubber or other suitable material provided around the periphery of a cover 37. The cover 37 has riveted or otherwise secured therein a boss 38 which forms the attaching means engaged by the nut 34. The outer surface of said boss is formed with coarse threads engaged by a winged nut 39 which in turn engages a yoke 40 provided with a suitable central opening through which the boss projects. The yoke 40 has oppositely directed notches 41 on downwardly turned ends thereof which engage diametrically disposed pins 42 secured to the can-shaped body 35 and hold the body tightly against said gasket when the nut 39 is rotated in one direction, and loosely, 30 so as to permit removal and refilling, when the nut 39 is rotated in the opposite direction. The boss is formed with a passage opening into the passage 30, and connecting to a conduit 43 secured to the boss and extending to the bottom of the can or body 35. This conduit is bent at such an angle that it opens from the side which is the lower side when the device is in use.

35 An internally and externally threaded ring 44 is shown threaded on the end of the body 10 opposite the handle 12, to form attaching means for

a shouldered clamp ring 46 which attaches to the end of the body two annular members 48 and 50. The member 48 forms a conical outlet for the liquid passage 30, and cooperates with a needle valve formed on the end of a rod 52.

The member 50 cooperates with the member 48 to form an annular air chamber 54 communicating with the air passage 16 through an opening in member 48. The members 48 and 50 define between them, at the left, an annular air passage or nozzle surrounding the end of the liquid outlet, whereby the air issuing under pressure atomizes and entrains the cleaning liquid and projects it against the work being cleaned.

The needle valve rod 52 has its end slidably seated in a plug 56 threaded into the handle 12, at one side of the passage 16 therein, and is provided with a collar 58, a valve-closing spring 60 being sleeved on the rod and compressed between the plug 56 and the collar 58. Both of the valves 28 and 52 are adapted to be opened by pressure on a lever or trigger 62 pivoted on the body 10.

The spray of air and cleaning liquid formed when the trigger 62 is pulled toward the handle 12 is directed against the surface of the work by a flaring elongated mouth or pressure nozzle 64, shown as diecast in one piece with an encircling wall 66 forming an annular suction mouth or nozzle 68 surrounding the pressure nozzle.

The wall 66 preferably projects slightly beyond the nozzle 64, to insure a good peripheral seal when the device is pressed against the surface of the work, as for example the upholstery of an automobile. The wall 66 projects far enough to sink into the upholstery to give an effective seal when the nozzle 64 is brought into engagement with the surface of the work. The casting 64-66 is attached to the cleaning device body 10 by means such as a clamp nut 70 engaging the ring 44. If desired it may also have secured thereto a stamping 72 formed with an opening sleeved on the boss 32.

The casting 64-66 is shown extended at one side, at right angles to the handle 12, to form an outlet 74 for the suction nozzle 68. The outlet 74 is thus conveniently arranged to serve as a second handle adapted to be grasped by the left hand of an operator whose right hand grasps the handle 12.

The outlet 74 has attached thereto a flexible conduit 76 leading to a portable suction unit. This unit is inclosed in a casing 80 mounted on a base 82, which may if desired be supported on casters 84.

The unit is provided, within this casing, with a motor 86 driving a centrifugal pump or fan having an impeller 88 directly driven by the motor 86 and arranged in a housing 90. The intake at the axis of the housing 90 is connected to the conduit 76. The outlet of the housing 90 is preferably in the form of an exhaust pipe 92 having secured thereto a flexible conduit 94 adapted to be projected out of doors below or through an opening in the sash 96 of a window in the wall 98 of the building in which the device is being used.

The motor 86 may be connected by a cord 100 to a base plug 102, and may be turned on and off by a suitable switch 104.

It will be seen that, with the motor 86 turned on, the device can be moved back and forth in engagement with the work, the valves 28 and 52 being held open by the trigger 62. This causes the cleaning liquid to be atomized and sprayed

into the surface of the work whence, after dissolving out grease spots and the like, it is continuously removed by the suction of the suction nozzle 68. Preferably the device is moved back and forth over the work a short time after the valves 28 and 52 are permitted to close, to leave as little of the cleaning liquid odor as possible.

Figures 3 and 4 illustrate an alternative construction in which parts corresponding to like parts in Figures 1 and 2 are designated by the same reference numerals plus 100. In this construction the cleaning liquid is supplied from a remote source through a hose or conduit 143 instead of from a container portable with the device. While the valve mechanism has not been shown in detail, it may be substantially similar to that of Figure 2.

A brush is mounted in the device to brush or scrub the material as it is cleaned and as shown includes a rod 163 rotatably mounted in the nozzle and having one or more rows of bristles 165 thereon. The rod extends across the nozzle 164 adjacent one edge thereof and the bristles 165 are of such a length as to extend slightly beyond the front plane of the nozzle as seen in Figure 3.

In order to rotate the brush, the nozzle 166 is formed at its ends with integrally cast walls 167 forming chambers 169 into which the ends of the rod 163 extend. The rod carries turbine wheels 171 in these chambers which are driven by compressed air conducted into the chambers by conduits 173 which extend into the chambers and terminate in nozzles 175 adjacent the turbine wheels. The conduits 173 preferably communicate with the compressed air passage posterior to the control valve so that the brush will be rotated when air is supplied to the spray but not otherwise.

The device of Figures 3 and 4 is used in substantially the same manner as that of Figures 1 and 2. When the nozzle is pressed against upholstery or other material cleaning liquid will be sprayed onto the material within the nozzle 164 and the material will be scrubbed or brushed while wet by the rotating brush. The cleaning liquid and any dirt particles loosened by the cleaning action will then be sucked from the material through the outer nozzle 166.

While two embodiments of our invention have been described in detail, it is not our intention to limit its scope to those particular embodiments, or otherwise than by the terms of the appended claims.

This application is a continuation in part of our copending application Serial No. 141,202, filed May 7, 1937.

What is claimed is:

1. A portable cleaning device, adapted to be passed over upholstery or the like which is to be cleaned, comprising a head adapted to contact the upholstery and which comprises a flared inner nozzle and an outer nozzle coaxial therewith and spaced therefrom to provide an annular zone between them and both of which are constructed to seal against said upholstery, a source of suction connected to one of said nozzles, a source of cleaning liquid and a source of fluid under pressure connected to the other of said nozzles, and means for causing the fluid under pressure to project the cleaning liquid through said nozzle against the upholstery in the form of a spray, said nozzles being rigid with the head and the outer nozzle projecting beyond the inner one to sink into the upholstery when

the upholstery is engaged by the inner nozzle, to give an effective peripheral seal.

2. A cleaning device comprising a body formed at one end to be grasped by an operator and having a liquid passage and a passage for pressure fluid extending therethrough and opening through the other end of the body adjacent each other, means for connecting the first passage to a source of cleaning liquid and the second passage to a source of pressure fluid, a nozzle mounted over the ends of said passages and including a central liquid projecting member communicating with the liquid passage and a member forming an annular chamber surrounding the central member and into which the pressure fluid passage opens and which has an outlet opening closely surrounding the outlet end of the central member and also including an elongated flaring mouth into which both of said members discharge, valves for said two passages, a single control for said valves, and a suction nozzle surrounding said flaring mouth to provide a suction zone for withdrawing cleaning liquid after acting on an article over which said associated nozzles are moved.

3. A cleaning device comprising a body formed at one end to be grasped by an operator and having a liquid passage and a passage for pressure fluid extending therethrough and opening through the other end of the body adjacent each other, means for connecting the first passage to a source of cleaning liquid and the second passage to a source of pressure fluid, a nozzle mounted over the ends of said passages and including a central liquid projecting member communicating with the liquid passage and a member forming an annular chamber surrounding the central member and into which the pressure fluid passage opens and which has an outlet opening closely surrounding the outlet end of the central member and also including an elongated flaring mouth into which both of said members discharge, and a suction nozzle surrounding said flaring mouth to provide a suction zone for withdrawing cleaning liquid after acting on an article over which said associated nozzles are moved.

4. A cleaning device comprising a body formed at one end to be grasped by an operator and having a liquid passage and a pressure fluid passage extending therethrough, means for connecting the first passage to a source of cleaning liquid and the second passage to a source of pressure fluid, a spray device mounted at the other end of the body and communicating with both of said passages to form a liquid spray, a nozzle secured to the body around the spray device to receive the spray therefrom and having a mouth adapted to be pressed against material to be cleaned, and a suction nozzle surrounding and spaced from said first named nozzle and providing a suction zone around said mouth for withdrawing cleaning liquid from the material as the cleaning device is moved over the material.

5. A cleaning device comprising a body formed at one end to be grasped by an operator and having a liquid passage and a pressure fluid passage extending therethrough, means for connecting the first passage to a source of cleaning liquid and the second passage to a source of pressure fluid, a spray device mounted at the other end of the body and communicating with both of said passages to form a liquid spray, a nozzle secured to the body around the spray device to receive the spray therefrom and having a mouth

adapted to be pressed against material to be cleaned, a scrubbing member movably mounted in said nozzle in engagement with the material, means for moving said member in the nozzle while said member is in engagement with the material, and a suction nozzle surrounding said first named nozzle and providing a suction zone around said mouth for withdrawing cleaning liquid from the material as the cleaning device is moved over the material.

6. A cleaning device comprising a body formed at one end to be grasped by an operator and having a liquid passage and a pressure fluid passage extending therethrough, means for connecting the first passage to a source of cleaning liquid and the second passage to a source of pressure fluid, a spray device mounted at the other end of the body and communicating with both of said passages to form a liquid spray, a nozzle secured to the body around the spray device to receive the spray therefrom and having a mouth adapted to be pressed against material to be cleaned, a brush rotatably mounted in said nozzle, means for rotating said brush, and a suction nozzle surrounding said first named nozzle and providing a suction zone around said mouth for withdrawing cleaning liquid from the material as the cleaning device is moved over the material.

7. A cleaning device comprising a body formed at one end to be grasped by an operator and having a liquid passage and a pressure fluid passage extending therethrough, means for connecting the first passage to a source of cleaning liquid and the second passage to a source of pressure fluid, a spray device mounted at the other end of the body and communicating with both of said passages to form a liquid spray, a nozzle secured to the body around the spray device to receive the spray therefrom and having a mouth adapted to be pressed against material to be cleaned, a brush rotatably mounted in said nozzle, fluid operated means for rotating the brush, a connection from the pressure fluid passage to the fluid operated means, and a suction nozzle surrounding said first named nozzle and providing a suction zone around said mouth for withdrawing cleaning liquid from the material as the cleaning device is moved over the material.

8. A cleaning device comprising a flaring nozzle, a spray device in said nozzle, means for conducting a cleaning liquid to the spray device to be sprayed through the nozzle onto material to be cleaned, a scrubbing member in the nozzle to engage and scrub the material, means to move said scrubbing member in the nozzle while said member is in engagement with the material, and a suction nozzle surrounding the first named nozzle and providing a suction zone for withdrawing cleaning liquid from the material.

9. A cleaning device comprising a flaring nozzle, a spray device in said nozzle, means forming a cleaning liquid passage and a gas pressure passage communicating with the spray device whereby cleaning liquid will be sprayed through the nozzle onto material to be cleaned, a scrubbing member movably mounted in the nozzle, fluid pressure means connected to said gas pressure passage for moving said scrubbing member, and a suction nozzle surrounding the first named nozzle and providing a suction zone for withdrawing cleaning liquid from the material.

10. A cleaning device comprising a flaring nozzle, a spray device in said nozzle, means forming a cleaning liquid passage and a gas pres-

sure passage communicating with the spray device whereby cleaning liquid will be sprayed through the nozzle onto material to be cleaned, a brush rotatably mounted in the nozzle, fluid pressure means connected to said gas pressure passage for rotating said brush, and a suction nozzle surrounding the first named nozzle and providing a suction zone for withdrawing cleaning liquid from the material.

11. A cleaning device, comprising a body formed at one end to be grasped by an operator and having a liquid passage and a passage for pressure fluid extending therethrough and opening through the other end of the body adjacent each other, means for connecting the first passage to a source of cleaning liquid and the second passage to a source of pressure fluid, a nozzle

5 mounted over the ends of said passages and including a central liquid projecting member communicating with the liquid passage and a member forming an annular chamber surrounding the central member and into which the pressure fluid passage opens and which has an outlet opening closely surrounding the outlet end of the central member and also including an elongated flaring mouth into which both of said members discharge, and a suction nozzle co-axial with and spaced from said flaring mouth to provide a suction zone for withdrawing cleaning liquid after acting on an article over which said associated nozzles are moved.
